UNITED STATES PATENT OFFICE.

JOHN P. SHIPMAN, OF ST. LOUIS, MISSOURI.

DESIGN FOR A WAGON-SUNSHADE IRON.

SPECIFICATION forming part of Design No. 31,471, dated August 29, 1899.

Application filed August 5, 1899. Serial No. 726,327. Term of patent 3½ years.

To all whom it may concern:

Be it known that I, JOHN P. SHIPMAN, a citizen of the United States, residing at St. Louis, State of Missouri, have invented a certain new and useful Design for Wagon-Sunshade Irons, of which the following is a specification.

In the drawings, Figure 1 is a perspective view, and Fig. 2 a side elevation, of the device. Fig. 3 is a view of the outer side of the device.

The design consists of a flat narrow plate 1, having its lower end square or straight, as at 2, and its upper end curved or rounded, as at 3. A bolt-hole 4 is formed centrally in the plate near its upper end, and rivet-holes 5 are formed above and below said bolt-hole. Projecting centrally from the outer side of

the plate, near its lower end, is a cylindrical projection 6, and projecting inward from the side edges of the plate at points coincident with the projection 6 are a pair of ears 7, which taper toward their inner ends and curve inward toward each other.

I claim—

The design for wagon-sunshade irons substantially as herein shown and described.

In testimony whereof I hereunto affix my signature, in the presence of two witnesses, this 27th day of July, 1899.

JOHN P. SHIPMAN.

Witnesses:

WILLIAM E. CLARK.

AUGUST KRIEGER.
